United States Patent

Des. 238,642

Patented Feb. 3, 1976

238,642

CABINET OR THE LIKE

Huey T. Keller, High Point, N.C., assignor to Hooker Furniture Corporation

Filed Apr. 17, 1972, Ser. No. 245,028

Term of patent 14 years

Int. Cl. D6—04

U.S. Cl. D6—164

fig. 3

FIG. 1 is a front elevational view of a cabinet or the like showing my new design, the rear thereof being substantially plain and unornamented;

FIG. 2 is a top plan view of such design; and

FIG. 3 is a side elevational view of the same, the opposite end being substantially a mirror image of that shown.

I claim:

The ornamental design for a cabinet or the like, as shown.
